UNITED STATES PATENT OFFICE.

ANGELO TESORONI, OF NEWARK, NEW JERSEY, ASSIGNOR TO SLOAN & COMPANY, OF NEWARK, NEW JERSEY, A CORPORATION OF NEW JERSEY.

BRACELET.

1,205,287.

Specification of Letters Patent. Patented Nov. 21, 1916.

Application filed June 2, 1916. Serial No. 161,227.

To all whom it may concern:

Be it known that I, ANGELO TESORONI, a citizen of the United States, and a resident of Newark, in the county of Essex and State 5 of New Jersey, have invented certain new and useful Improvements in Bracelets, of which the following is a specification.

This invention relates to a bracelet of novel construction, which is of attractive 10 appearance, possesses superior flexibility, and may be readily assembled.

In the accompanying drawing:—Figure 1 is an outer face view of a portion of a bracelet embodying my invention; Fig. 2, an inner face view thereof; Fig. 3, a side view partly in section; Fig. 4 a cross section; Fig. 5, a detail of one of the blanks; Fig. 6, a perspective view of the blank after being bent; Fig. 7, a perspective view of one of 20 the staples, and Fig. 8, a side view on a smaller scale, showing the bracelet complete.

The body of the bracelet is composed of a series of links, and of a series of staples connecting the links. Each link is hollow and 25 of oblong form, being so bent as to form an outer section 1, a pair of parallel side sections 2, and an inner section 3. The outer section 1, is arched, and of a length constituting the width of the bracelet, so that when 30 the parts are assembled, the convex edge of any one link will be opposed to the concave edge of the adjoining link, thus producing an attractive "scaly" appearance. The sides 2 of the links correspond in length to 35 the thickness of the bracelet, while the inner section 3 parallels the outer section and is made of the same length as the latter. Each link is furnished at its concave edge with a step-shaped extension or lining 4 which is 40 shown to be made integral with the link but may be soldered thereto if desired. This extension underlies the joint between the link to which it is attached, and the convex edge of the adjoining link, so that the several extensions prevent the formation of objectionable slits between the links, especially 45 when the bracelet is closed upon the arm.

Each side section 2 is apertured as at 5, the apertures of adjoining links being engaged by the shanks of a common staple 6.

In this way, there appears along each rim of the bracelet, a continuous row of staples, the construction of the parts being such that a slight play is by the staples permitted between the links, so that the entire body of 55 the bracelet is flexible. The bottom sections 3 are of a width to permit this slight play, there being formed between them in the unflexed position of the bracelet, a series of parallel slits 7 (Fig. 2).

In constructing the bracelet, a flat blank is struck up by means of a suitable die so as to embody a central arched section and a pair of diametrically extending apertured shanks (Fig. 5). The step-shaped extension or lining 4 when made integral with the blanks is struck up simultaneously with the latter, or when made in a separate piece is subsequently soldered thereto. The blank is now bent into the form of a staple of which the 60 arched central section forms the cross piece (Fig. 6). The links are now connected by means of the staples 6, the ends of which are upset against the inner faces of the side pieces. Next, the two shanks of each link 65 are at a point beyond the apertures 5, bent inwardly at right angles, so as to parallel the outer link section 1, the length of the shanks being such that their free ends will contact with each other (Fig. 4). These 70 free ends are soldered together as at 8 so as to form the continuous inner section 3 and to thus close the link which will now assume the squared or oblong form shown.

Fig. 8 shows the bracelet in the flexed position assumed when encircling the arm of the wearer, it being understood that the bracelet is furnished with a suitable clasp, which is not shown in the drawing for the reason that the device is here represented 80 in its closed position.

I claim:

1. A bracelet comprising a series of oblong links, having outer sections, a pair of apertured sides and continuous inner sections, and two rows of staples extending 95 along said apertured sides, the shanks of said staples engaging the sides of adjoining links.

2. A bracelet composed of a plurality of 100

closed hollow links having arched outer sections, apertured side sections, and continuous inner sections that parallel the outer sections, and of staples engaging the apertured side sections.

3. A bracelet composed of a plurality of closed hollow oblong links, having arched

outer sections, apertured side sections, and continuous inner sections, linings carried by the outer sections and underlying the joints 10 between said sections, and staples engaging the apertured side sections.

ANGELO TESORONI.
